UNITED STATES PATENT OFFICE.

JOHN W. COAST, JR., OF TULSA, OKLAHOMA, ASSIGNOR TO THE PROCESS COMPANY, A CORPORATION OF MARYLAND.

ART OF TREATING HYDROCARBONS.

1,333,964.

Specification of Letters Patent. Patented Mar. 16, 1920.

Application filed May 5, 1917. Serial No. 166,524.

To all whom it may concern:

Be it known that I, JOHN W. COAST, Jr., a citizen of the United States of America, a resident of Tulsa, in the county of Tulsa, 5 State of Oklahoma, have invented certain new and useful Improvements in the Art of Treating Hydrocarbons, of which the following is a full, clear, and exact description, reference being had to the accompanying drawings, forming a part of this specification.

My invention relates to improvements in the art of treating hydrocarbons, and more particularly to a method of cooling hydrocarbon vapor and at the same time heating 15 a body of liquid. The new method may be followed in cracking petroleum hydrocarbons under pressure, to obtain a product known as gasolene, or cracked gasolene. In 20 cracking such hydrocarbons, the vaporized fractions having relatively high boiling points should be condensed and returned to the still for further treatment, and the fresh charge of oil should be heated before it reaches the still. One of the objects of my 25 invention is to provide a simple and efficient method of accomplishing these results.

In the preferred form of the invention, a body of relatively cool liquid is maintained 30 in a heat exchanger, and the hot vapor passing from the still is discharged into this liquid. The hot vapor is permitted to rise in the form of bubbles in the relatively cool liquid, thereby heating the liquid and at 35 the same time condensing the previously vaporized fractions having relatively high boiling points. The body of liquid maintained in the heat exchanger may be formed partly by the high boiling point condensate, 40 and partly by a fresh charge of oil. In this event, the hot condensate will serve as a heating medium for the fresh charge of oil, and the liquid mixture will be constantly subjected to the heat of the vapor 45 which bubbles through the liquid. Some of the liquid will be converted into vapor and pass to a condenser. The heated liquid preferably overflows and passes to the still. Some of this overflowing liquid is condensate 50 formed by condensing the high boiling point fractions, and some of it is preferably a fresh charge of oil which has been subjected to the heat of the vapor and condensate.

The drawing is a diagrammatical view of 55 an apparatus adapted for use in carrying out my method.

To illustrate the invention, I have shown a cracking apparatus comprising a pressure still 1 arranged above a heating chamber 60 2, a vapor pipe 3 leading from the still to a heat exchanger A, a vapor pipe 4 connecting the heat exchanger to an air cooled reflux condenser 5, and a vapor pipe 6 connecting said reflux condenser to a water 65 cooled condenser 7, from which the product is recovered. A pressure regulating valve 8, in the vapor pipe 6, may be regulated to maintain a predetermined pressure in the reflux condenser, heat exchanger A, and 70 also in the still 1. A perforated discharge member 9, connected to the vapor pipe 3, is submerged in a relatively cool body of hydrocarbon liquid contained in a reservoir 10. These members 9 and 10 form part of 75 the heat exchanger A. An overflow pipe 11, provided with a liquid seal, or trap, 12, leads from the surface of the liquid in the reservoir 10 to the lower portion of the still 1. A pump 13 may be used to force 80 a fresh charge of relatively cool hydrocarbon oil through a pipe 14 and into the reservoir 10.

The new method may be followed in cracking various heavy hydrocarbon products resulting from the treatment of crude petroleum, particularly such inexpensive hydrocarbons having boiling points higher than 350° F., the most beneficial results being obtained from hydrocarbons having 85 boiling points ranging from 450° F. to 700° F. The valve 8 in the vapor pipe 6 is adjusted to obtain the desired pressure in the still, heat exchanger A and reflux condenser 90 5. The pressure may range from 50 to 150 95 pounds per square inch, or even higher, but it is preferably maintained at about 85 pounds per square inch. The contents of the still are preferably subjected to such a high degree of heat that the hydrocarbon 100 liquid will vaporize very rapidly. This temperature may range from about 600° F. to 800° F., and is preferably about 725° F.

Owing to the intense heat and the rapid vaporization, a large volume of unconverted, or partially converted, hydrocarbons will 105 flow from the still 1 to the heat exchanger A. At this point the numerous small streams of

vapor discharged from the submerged perforated member 9, rise in the form of bubbles in the relatively cool hydrocarbon liquid, thereby heating said liquid, and at the 5 same time condensing the previously vaporized fractions having relatively high boiling points. By bubbling the vapor through a relatively cool liquid, as herein shown, all of the vapor is very effectively subjected to the 10 action of the cool liquid, and the heaviest fractions are condensed and prevented from passing to the main condenser. The heat exchanger therefore constitutes a highly efficient condenser for the high boiling point 15 fractions. The hottest portion of the liquid overflows from the heat exchanger and passes through the overflow pipe 11 to the still 1.

The fresh charge of relatively cool oil, 20 flowing from the pipe 14, commingles with the hot condensate in the heat exchanger A, and is also subjected to the high temperature of the hot vapors bubbling through the liquid mixture in the heat exchanger. The 25 fresh charge of oil is thus subjected to a very high temperature, and thoroughly heated, before it overflows at the surface of the liquid body in the heat exchanger.

The reflux condensate, flowing from the 30 condenser 5, passes through the pipe 4 and commingles with the liquid in the heat exchanger, this condensate being heated before it overflows to the still.

The desirable low boiling point fractions 35 flow from the reflux condenser 5, through the vapor pipe 6, and into the main condenser 7, where they are condensed to form the low boiling point product.

It will now be understood that the hot 40 vapor, bubbling through the hydrocarbon liquid in the heat exchanger, is cooled so as to separate the high boiling point fractions from the lighter fractions; the hot condensate returns freely to the still; the fresh 45 charge of oil is thoroughly heated by the vapor and also by the hot condensate; the heat exchanger also serves as means for heating the reflux condensate flowing from the condenser 5, and although the vapor is 50 bubbled through the liquid, it will be apparent that the heat exchanger will perform its several functions while maintained under the high pressure which must necessarily be employed in cracking petroleum hydrocar- 55 bons.

I claim:—

1. In the art of treating petroleum hydrocarbons, the method which comprises maintaining a body of hydrocarbon liquid in a reservoir, vaporizing and cracking hydrocarbon liquid in a still, conducting vapor from the still and discharging it into said hydrocarbon liquid in the reservoir at points below the surface of the liquid, permitting the hot vapor to rise freely in the form of bubbles in the liquid in said reservoir, thereby heating the last mentioned liquid and at the same time condensing high boiling point fractions in the vapor, conducting vapor from the surface of the liquid in said reservoir and through a reflux condenser to a main condenser, returning high boiling point condensate from said reflux condenser to said reservoir, so as to subject such condensate to the hot vapor bubbling through said reservoir, permitting the heated condensate to overflow from said reservoir, and conducting the overflowing condensate into said still. 60 65 70 75

2. In the art of cracking petroleum hydrocarbons, the method which comprises maintaining a body of relatively cool liquid in a reservoir, vaporizing and cracking hydrocarbon liquid in a still, conducting vapor from the still, dividing the vapor into numerous small streams and at the same time discharging the streams of hot vapor into said body of relatively cool liquid at points below the surface thereof, permitting the numerous streams of hot vapor to rise freely in the form of bubbles in the relatively cool liquid in said reservoir, thereby heating the last mentioned liquid and at the same time condensing high boiling point fractions in the vapor, conducting vapor from the surface of the liquid in said reservoir and through a reflux condenser to a main condenser, returning high boiling point condensate from said reflux condenser to said reservoir, so as to subject such condensate to the streams of hot vapor bubbling through said reservoir, permitting the heated condensate to overflow from said reservoir, conducting the overflowing condensate into said still, and maintaining said still and reservoir under a pressure greater than 50 pounds per square inch. 80 85 90 95 100 105

In testimony that I claim the foregoing I hereunto affix my signature.

JOHN W. COAST, JR.
